UNITED STATES PATENT OFFICE

158,617

SWIVELING COUNTER DISPLAY LAMP OR THE LIKE

Charles S. Rosenberg, Chicago, Ill.

Application April 22, 1949, Serial No. 2,201
Term of patent 14 years

(Cl. D48—20)

To all whom it may concern:

Be it known that I, Charles S. Rosenberg, a citizen of the United States, residing in Chicago, Cook County, Illinois, have invented a new, original, and ornamental Design for a Swiveling Counter Display Lamp or the like, of which the following is a specification, reference being had to the accompanying drawing, forming a part hereof.

In the drawing:

Figure 1 is a top view of a swiveling counter display lamp, showing my new design;

Figure 2 is a side elevational view thereof in one position of the parts; and

Figure 3 is a view similar to Figure 2 but on a smaller scale, and showing the upper part of the lamp turned to the other side.

I claim:

The ornamental design for a swiveling counter display lamp or the like, substantially as shown.

CHARLES S. ROSENBERG.
